UNITED STATES PATENT OFFICE.

JOHN L. RICHTER, OF ALAMEDA, CALIFORNIA, ASSIGNOR TO UNITED STATES FAUCET CO., OF SAN FRANCISCO, CALIFORNIA, A CORPORATION OF CALIFORNIA.

PIPE-CLEANING DEVICE.

1,149,164.

Specification of Letters Patent.

Patented Aug. 3, 1915.

Application filed July 28, 1914. Serial No. 853,638.

To all whom it may concern:

Be it known that I, JOHN L. RICHTER, a citizen of the United States, residing at Alameda, in the county of Alameda and State 5 of California, have invented new and useful Improvements in Pipe-Cleaning Devices, of which the following is a specification.

The present invention relates to an apparatus for washing and cleansing tubes and 10 coils through which there may be circulated or moved various materials, such as wines, beer, and other liquors, and particularly relates to beer pipe and coil cleaners.

It is one of the objects of the present invention to provide a cleaner whereby water 15 may be transmitted to and through pipes, coils and other connections which are utilized in the handling of beer or other liquors.

It is a particular object of the present invention to provide an apparatus, including 20 a pump, a receptacle for a cleansing solution, and means for connecting the pump to the beer dispensing apparatus, whereby the solution may be driven through the beer 25 pipes and coils in opposite directions for the effectual cleaning of the same. It is another object of the invention to provide an extremely simple, inexpensive and reliable circulating apparatus including a double-acting 30 pump, a suitable valve with means for connecting the valve to the pipe system to be cleansed, and means for returning the solution to a tank to which the pump is connected for the return of the solution to the 35 pipe system.

The invention consists of the parts and the construction and combination of parts 40 as hereinafter more fully described and claimed, having reference to the accompanying drawings, in which—

Figure 1 is a diagrammatic view showing the present circulating apparatus as connected to apparatus for the dispensing of beer. Fig. 2 is a central vertical section 45 through the pump, showing some of the parts in elevation. Fig. 3 is a detail view of the four-way valve fitting.

The invention comprises a suitable tank or receptacle 2 for the reception of a solution of suitable character which is adapted 50 to be circulated back and forth through a system of pipes and connections which are to be cleansed, and which system is shown

as including a beer faucet 3, Fig. 1, which is shown as connected to a cooling coil 4. This 55 in turn is connectible by a hose 5 with a keg 6 from which the beer or other liquor is to be drawn. The tank 2 may be charged with a solution through an aperture 7 closed by a 60 plug 8.

Secured to the top of the receptacle 2 is a pump 9, having at its lower end a valve seat 10 upon which seats a valve disk 11. Reciprocable in the pump cylinder 9 is a piston 12 provided with a packing ring 13; the piston 12 being provided with a removable valve seat 14 upon which seats an upper valve disk 15. The piston 12 is connected to the lower end of a suitable piston-rod 16, which is here shown as tubular and closed at its 70 lower end just above the upper valve 15, there being provided lateral ports 17 for the flow of liquor from below the valve 15. The piston-rod 16 is actuated from its upper end by a suitable handle 18. A packing 75 gland 19 is connected to a suitable fitting 20, attached to the upper end of the pump cylinder 9, the fitting 20 having an outlet port 21 on one side and is connected at the same side to a suitable valve 22 by which the fluid 80 passing from the port 21 of the head fitting 20 is controlled in direction of flow.

The body of the valve 22 is provided on one side with a chamber 23, to the lower end of which is connected a return pipe 24, this 85 being also fitted at its lower end into the top of the tank 2. The valve or cock 22 is of the four-way type, having opposite discharge nipples 25 and 26 through which the fluid may be alternately directed by the 90 movement of the valve shaft 27 through the manipulation of its handle 28. When turned to the position indicated in Fig. 3, the fluid from the pump flows in the direction of the arrows, as indicated. 95

When the apparatus is to be used, a suitable connection is made between the beer faucet 3 and the beer pipe 5, in this instance there being connected to the valve nipple 25 a hose 29 which is connected also to the beer faucet 3, and connected to the valve nipple 26 is a hose 30, the opposite end of which is connected by a suitable coupling 31 to the end of the beer pipe 5 which is disconnected from the tap tube in the keg 6. 100

The operation of this apparatus is as fol-

lows: The beer pipes and their connections may be washed with clear water from any suitable source. In this instance there is provided, as shown in Fig. 1, a wash water pipe 32 which is connected to a cock 33 connected to the pump head fitting 20. When the cock 33 is opened, wash water may then be admitted through the hose 32 and through the head fitting 20 and thence directed by the valve 22 through the hose 30 and its connected beer hose 5; thence through the beer coil 4 and from the faucet 3 into the adjacent sink or drain not shown. When the beer pipes are being washed, the hose 29 is omitted so that the water may run freely from the supply connection 32 through the head gear of the pump, through the pipe 30 and coil 4 and discharge from the faucet 3. After having sufficiently washed the beer pipes and connections thereto, the operator connects the pipe or hose 29 to the faucet 3 and the nipple 25 of the valve 22, closes the cock 33 and then reciprocates the pump piston 12 through means of the handle 18. As the piston moves upwardly, the upper valve 15 closes and the suction therebelow draws the solution from the tank 2 up past the lower valve disk 11; any fluid in the pump cylinder 9, above the valve disk 15, being discharged on the upward movement of the valve 15. When the movement of the piston 12 is reversed and it moves downwardly, the lower valve disk 11 seats and the fluid thereabove is discharged past the upper valve 15 and is displaced by the downwardly moving plunger 16 and forced through the valve 22 out of one or the other of its nipples 25 or 26, as determined by the position of the valve shank 27. Assuming that the fluid solution from the tank 2 discharges through the nipple 25 and thence through the pipe 29, coil 4, and beer hose 5, it will then return through pipe 30 to the nipple 26 of the valve 22 and be directed by the valve shank 27 down the chamber 23, from which it will pass down the return pipe 24 to the tank 2 for recirculation through the connected apparatus and system in one direction, so long as the valve shank 27 is not moved. Because of the fact that generally in beer dispensing devices the liquor flows in one direction all the time, it is desirable that the movement of the cleansing solution can be reversed or sent in either direction alternately for the more effectual cleaning of the beer pipes and their connections. Therefore, after having forced the cleansing solution through the system in one direction for a period of time, the operator reverses the position of the valve shank 27 so as to direct the flow of solution from the pump through the valve nipple 26, for instance, when it will move down the pipe 30, up through the coil 4,

and back through the hose 29 into the nipple 25 from which it will flow down the return chamber 23 to the tank.

From the foregoing it will be seen that I have provided a simple, practicable, efficient and substantial apparatus for the ready washing of a system of tubes or pipes through which a liquor may move, and by which apparatus a cleansing solution can be forced through the system in either direction alternately. After the beer pipes and their connections have been sufficiently washed and cleansed, the hose 29 is disconnected from the faucet 3 and the hose 30 disconnected from the beer hose 5. The latter is then connected to the tap tube of the beer keg and the beer may be again drawn from the keg.

Having thus described my invention, what I claim and desire to secure by Letters Patent is—

85

1. A pipe cleaning device comprising, in combination, a liquor handling apparatus, a valve casing having opposing side ports, a flexible connection joined to each side port of the valve casing and connected to a respective end portion of the liquor handling apparatus, said valve casing having a lateral and vertical outlet port interposed between the side ports, and also an intake passage opposing the outlet, a single tank, a pump fixed on the tank and extending vertically therefrom, said pump having a removable head fixed to the valve casing and provided with a passage forming a continuation of the casing intake passage, a return pipe fixedly secured to the tank and connected to the vertical outlet port of the valve casing, and a four way valve arranged in the valve casing to connect the intake with either of the side ports and the unconnected side port with the lateral outlet port, whereby the solution from the tank will flow through the pump, valve, liquor handling apparatus and back through the valve and return pipe to the tank in the first instance.

105

2. An apparatus for washing and cleansing a liquor handling apparatus comprising a solution tank, a pump extending vertically from the tank and including a valve normally and automatically closing the connection between the pump and tank, a head fitting for the pump having a fixed valve casing projecting laterally over the tank, said casing having an intake communicating with the pump, opposing side ports adapted to be connected to the liquor handling apparatus, and a lateral outlet port terminating downwardly in opposing relation with the tank, a return pipe connecting the downward terminal of the casing outlet with the tank, a valve in the casing for controlling the ports, and a second laterally extending

115

120

125

valve connected with the opposite side of the head fitting and adapted to be connected with a liquid supply for washing the apparatus, the automatic valve of the pump preventing the intermixing of the fluids when the second valve is opened.

In testimony whereof I have hereunto set

my hand in the presence of two subscribing witnesses.

JOHN L. RICHTER.
